CLAIM

The ornamental design for a chair trim extrusion, as shown and described.

DESCRIPTION

FIG. 1 is a perspective view of a chair trim extrusion of the present invention, broken in the center to indicate indeterminate length;

FIG. 2 is a front elevation view thereof, the rear elevation view being a mirror image thereof;

FIG. 3 is a left side elevation view thereof, the right side elevation view being a mirror image thereof;

FIG. 4 is a top plan view thereof; and,

FIG. 5 is a bottom plan view thereof.
